UNITED STATES PATENT OFFICE

GEORGE J. KORAN, OF KANSAS CITY, KANSAS

DESIGN FOR A RADIO SPEAKER BAFFLE UNIT OR SIMILAR ARTICLE

Application filed August 15, 1929. Serial No. 32,413. Term of patent 14 years.

To all whom it may concern:

Be it known that I, GEORGE J. KORAN, a citizen of the United States, residing at Kansas City, in the county of Wyandotte and State of Kansas, have invented a new, original and ornamental Design for a Radio Speaker Baffle Unit or Similar Article, of which the following is a specification, reference being had to the accompanying drawing, forming part thereof.

Figure 1 is a view in elevation of a radio speaker baffle unit or similar article embodying my design;

Figure 2 is an edge view of Figure 1.

I claim:—

The ornamental design for a radio speaker baffle unit or similar article, as shown.

GEORGE J. KORAN.
